UNITED STATES PATENT OFFICE

EMERY L. WALKER, OF WAUWATOSA, AND ARTHUR W. WERNER, OF MILWAUKEE, WISCONSIN, ASSIGNORS TO KIECKHEFER CONTAINER COMPANY, OF MILWAUKEE, WISCONSIN, A CORPORATION OF MAINE

PRINTING MACHINE

Application filed March 14, 1930. Serial No. 435,804.

This invention relates to improvements in printing machines.

In the paper box making industry, the printing upon the cartons or containers is performed upon the flat cardboard before all the steps necessary to produce the container are completed. Heretofore, a heavy ink very similar to paint has been used. This ink was very slow in drying, and consequently, the remaining steps in producing the container had to be postponed for a considerable period of time to prevent smearing of the ink before it had become sufficiently dry. Various attempts were made to use a fast drying ink, but these were unsuccessful due to the fact that in the ordinary type of press either a "ducking" roller or a plurality of transfer rollers are employed to transfer the ink from the inking means to the impression roller. With the "ducking" roller or with a plurality of transfer rollers, too great an interval of time elapses in the transfer of the ink, and if the latter is of a rapidly drying character it will harden and build up upon the rollers thereby making frequent removal and cleaning necessary. Furthermore, in the ordinary type of press, no means is provided for keeping the transfer roll in constant contact with fresh ink to permit the latter to redissolve unused ink upon the transfer roller.

It is one of the objects of this invention to overcome the above mentioned difficulties and to provide a printing machine which is designed to use a fast drying ink, and which is so constructed as to prevent the ink from drying and building up on the rollers.

A further object of this invention is to provide a printing machine in which the transfer roller is at all times kept in direct contact with fresh ink so that unused ink upon the transfer roller will be immediately redissolved.

A further object of this invention is to provide a printing machine in which a substantial body of fresh ink in liquid form is kept in constant contact with one of the rollers to feed ink thereto, and to keep all ink thereon in a solvent state so as to eliminate the possibility of ink drying and building up on said roller or on adjacent rollers.

A more specific object is to provide an improved printing machine employing a grooved ink measuring roller, a transfer roller, and an impression roller, in which an upper portion of the ink measuring roller is engaged by a doctor blade and in which a continuous flow of ink is applied behind said doctor blade to maintain at all times a substantial body of ink between said doctor blade and the roller.

A further object of this invention is to provide an improved printing machine which is efficient in operation and well adapted for the purpose described.

With the above and other objects in view, this invention consists of the improved printing machine, and all its parts and combinations, as set forth in the claims, and all equivalents thereof.

In the accompanying drawings, illustrating one complete embodiment of the preferred form of the invention, in which the same reference numerals designate the same parts in all of the views:

Fig. 1 is a side elevation of a portion of a printing machine embodying the improved features;

Fig. 2 is a plan view thereof;

Fig. 3 is an enlarged sectional view taken on line 3—3 of Fig. 2;

Fig. 4 is a view similar to Fig. 3, the end shield, however, being shown in vertical section;

Fig. 5 is a detail view showing a portion of the ink measuring roller and adjacent mechanism, parts being broken away;

Fig. 6 is a detail plan view of the doctor blade adjusting mechanism; and

Fig. 7 is a fragmentary sectional view showing a modified form of construction.

Referring to the drawings, the numeral 8 designates a frame portion for supporting a platform 9 over which sheets of material upon which printing is to be done are adapted to be passed. The vertical frame portions extend upwardly above the platform as at 10 to support upper side rails 11. Positioned between spaced apart guide members 12 on each side of the frame, are vertically mov-

able bearing blocks 13 which are engaged by the lower ends of coil springs 14.

Journalized in the bearing blocks is a shaft 15 carrying a rigidly mounted impression roller 16. The latter roller carries on its outer surface curved plates 17 formed with raised characters 18 thereon, which when suitably inked are adapted to create printed matter upon sheets of material which are engaged by the roller.

A supporting roller 19, which is positioned below a recess in the platform 9, is mounted rigidly on a shaft 20. The said shaft which is journaled below the platform carries on one end a rigidly mounted gear 21 which meshes with a gear 22 rigidly mounted on the shaft 15. The shaft 20 also carries a rigidly mounted sprocket wheel 20' which is connected by a sprocket chain 21' with suitable driving mechanism (not shown).

Extending laterally from the upper portions of the members 12, on each side of the frame, are supports 23 between which rods 24 extend. Mounted on said rods and extending between said supports is a drip pan 25 having lower openings 26 therein to which pipes 27 are connected, the said pipes leading to an ink circulating system (not shown).

A shaft 28, journaled in bearings 29 on the supporting members 23, carries a rigidly mounted ink measuring roller 30, the said roller having a plurality of grooves 31 extending around its outer periphery. Another shaft 32, which is journaled in bearings 33, carries a rigidly mounted transfer roller 34. The outer surface of said roller is preferably constructed of soft material such as rubber. The transfer roller engages both the ink measuring roller 30 and the impression roller 16 and is adapted to pick up a measured supply of ink from the grooves of the roller 30 and to transfer the same to the impression roller.

Upright members 35, which project from the members 12 on each side of the frame have a rod 37 extending therebetween. A plurality of doctor blade supporting brackets 38 each have a bore 39 in the upper portion thereof through which the rod 37 loosely extends. The lower portions of said brackets connect with the upper edge of a doctor blade 40 to support the latter. Extending upwardly from each of said brackets is an arm 41 having a forked upper portion 42. A collar 43 mounted rigidly on the rod 37 adjacent each bracket 38 also has an upwardly extending arm 44, said arm having a perforation in its upper end.

Arms 45 have lower handle portions 46 and upper forked portions 46', said forked portions each having two sets of perforations 47 and 48 therein. A pin extends through the perforations 48 and the perforation in the upper end of the arm 44 to connect the latter to the arm 45. An adjustment mem-

ber is provided with an outer threaded portion 49, with an intermediate slotted portion 50, and with an inner upwardly curved portion 51 having a perforation in its end terminating at 47. A pin extends through said 70 perforations and through the perforations 47 in the arm 45 to connect the adjustment member to said arm. A coil spring 52, which surrounds the threaded portion 49 of the adjustment member is positioned between a collar 53 and a nut 54. It may readily be seen that by turning the nut 54 the doctor blade 40 will be caused to more firmly engage the ink measuring roller 30. By pulling up on the handle portions 46 of the 80 arms 45, the doctor blades may be moved a considerable distance away from the roller to facilitate the removal of parts.

A pipe 55, which is connected with an ink circulating system has branches 56 extending therefrom, the said branches connecting with a feed pipe 57 having lower perforations 58 therein through which ink is caused to flow upon the ink measuring roller.

At each end of the rollers 30 and 34 are 90 end shields 59, each shield having a semi-circular portion 60 extending vertically and partially surrounding the shaft 28, and having another semi-circular portion 61 extending horizontally and partially surrounding 95 the shaft 32. Brackets 64 extending upwardly from the drip pan 25 further support the end shields. Each shield is also formed with interior passageways 62 which direct ink from the ends of the rollers to a lower 100 opening 63 in the shield through which the ink is discharged into the drip pan 25. The shields are supported by the shafts 28 and 32.

In the modified construction shown in Fig. 7, two doctor blades are employed, one 105 for the transfer roller and one for the ink measuring roller. The second doctor blade 40' is connected to the collar 43 behind the collar 38, and in this modification both collars are loose on the shaft 37.

In use, the ink is deposited in a continuous flow upon the grooved roller 30 and a substantial body of said ink accumulates behind the doctor blade 40. As the roller 30 rotates during operation, all ink is removed 115 from that portion of the roller which passes the doctor blade 40 except the measured quantity contained by the grooves 31 of the roller. The measured quantity of ink is then picked up from the grooves by the soft transfer roller 34 and is applied to the impression roller 16. Any ink left upon the transfer roller after contact with the impression roller will be immediately redissolved by the direct contact with fresh ink on the grooved roller. 125 In the ordinary type of press, where the transfer roller reciprocates back and forth between the inking roller and the impression roller, or where a plurality of transfer rollers are employed, there will be too great an in- 130

terval of time between the reception of ink from the inking roller and the delivery of said ink to the impression roller, and if a rapidly drying ink is used, it will harden and 5 build up on the rollers making frequent cleaning necessary. In applicant's device, a single transfer roller only is used, and said roller is always in contact with the fresh ink on the inking roller so that unused ink is 10 almost instantaneously redissolved.

As there is a continuous flow of ink on the inking roller 30 behind the doctor blade, the ink will naturally flow off at the ends of the roller. The said ink is guided by the passageways 62 in the end shields to the drip pan 25. From the drip pan the ink is directed by the pipe 27 to an ink circulating system (not shown) the said system adding vehicle to the ink and returning it to the feed 20 pipe 57 as fully set forth in a co-pending application of applicant's Serial Number 435,803.

Although only two forms of the invention have been shown and described, it is not desired to be limited to the exact showing, as 25 the broad concept of the invention includes all changes and modifications as may come within the scope of the claims.

What we claim is:

30 1. In a printing machine, a rotatably mounted impression roller for printing upon material engaged thereby, a rotatably mounted ink measuring roller, means for keeping a substantial body of ink in fluid form in direct contact with an upper portion of said ink measuring roller to supply ink thereto, and a rotatably mounted transfer roller directly engaging said ink measuring roller and said impression roller for transferring ink to the latter, said body of ink serving to redissolve unused ink upon the ink measuring roller and the solvent ink on the ink measuring roller serving to redissolve unused ink on the transfer roller.

45 2. In a printing machine, a rotatably mounted impression roller for printing upon material engaged thereby, a rotatably mounted grooved ink measuring roller, a doctor blade for keeping a substantial body of ink in fluid form in direct contact with said ink measuring roller to supply ink thereto, said doctor blade serving to remove all ink from the portion of the roller which passes it except that contained by the grooves therein, and a rotatably mounted transfer roller engaging said ink measuring roller and said impression roller for transferring a measured quantity of ink to the latter, said body of ink serving to redissolve unused ink upon the ink measuring roller and the solvent ink on the ink measuring roller serving to redissolve unused ink on the transfer roller.

50 3. In a printing machine, a rotatably mounted impression roller for printing upon material engaged thereby, a rotatably mount-

ed ink measuring roller, a doctor blade for keeping a substantial body of ink in fluid form in direct contact with said ink measuring roller to supply ink thereto, a rotatably mounted transfer roller engaging said ink measuring roller and said impression roller for transferring a measured quantity of ink to the latter, and a doctor blade engageable with a portion of said transfer roller prior to reception of a new supply of ink by 70 said portion, said body of ink serving to redissolve unused ink upon the ink measuring roller and the solvent ink on the ink measuring roller serving to redissolve unused ink on the transfer roller. 75

4. In a printing machine, a rotatably mounted impression roller for printing upon material engaged thereby, a rotatably mounted ink measuring roller, a doctor blade for keeping a substantial body of ink in fluid form in direct contact with said ink measuring roller to supply ink thereto, a rotatably mounted transfer roller engaging said ink measuring roller and said impression roller for transferring a measured quantity of ink to the latter, a doctor blade engageable with a portion of said transfer roller prior to 80 reception of a new supply of ink by said portion, said body of ink serving to redissolve unused ink upon the ink measuring roller and the solvent ink on the ink measuring roller serving to redissolve unused ink on the transfer roller. 85

5. In a printing machine, a rod spaced from said roller and extending parallel thereto, a bracket pivoted to said rod, an arm extending from said bracket, a lever arm pivotally associated with said rod, and a link connecting said lever arm with the arm on the doctor blade bracket, said lever arm being movable to cause disengagement of the doctor blade from the roller. 100

6. In a printing machine, a pair of cooperating rollers, a rod spaced from said rollers and extending parallel thereto, a bracket pivoted to a said rod, a doctor blade carried by said bracket and engageable with one of said rollers, another bracket pivoted to said rod, a doctor blade carried by said second bracket and engageable with the other roller, arms extending from said bracket, and a common adjustment member associated with said arms for regulating said doctor blade. 110

7. In a printing machine, a pair of cooperating rollers, a rod spaced from said rollers and extending parallel thereto, a bracket pivoted to said rod, a doctor blade carried by said bracket and engageable with one of said rollers, another bracket pivoted to said rod, a doctor blade carried by said second bracket and engageable with the other roller, arms extending from said brackets, a lever arm pivot- 125

ally associated with the arm of one of said brackets, and a link connecting said lever arm with the other of said bracket arms, said lever arm being movable to cause disengagement of both of the doctor blades from the rollers.

8. In a printing machine, a rotatably mounted impression roller for printing upon material engaged thereby, a rotatably mounted ink measuring roller, a doctor blade for keeping a substantial body of ink in fluid form in direct contact with said ink measuring roller to supply ink thereto, a rotatably mounted transfer roller engaging said ink measuring roller and said impression roller for transferring ink to the latter, said body of ink serving to redissolve unused ink upon the ink measuring roller and the solvent ink on the ink measuring roller serving to redissolve unused ink on the transfer roller, and end shields having reversely curved portions adjacent the ends of both the transfer roller and the ink measuring roller for conducting surplus ink away from said ends.
9. In a printing machine, a rotatably mounted impression roller for printing upon material engaged thereby, a rotatably mounted ink measuring roller, a doctor blade for keeping a substantial body of ink in fluid form in direct contact with said ink measuring roller to supply ink thereto, a rotatably mounted transfer roller engaging said ink measuring roller and said impression roller for transferring ink to the latter, said body of ink serving to redissolve unused ink upon the ink measuring roller and the solvent ink on the ink measuring roller serving to redissolve unused ink on the transfer roller, and end shields having reversely curved portions adjacent the ends of both the transfer roller and the ink measuring roller, said end shields having passages therein for directing the ink from the ends of the rollers to a point of discharge.
10. In testimony whereof we affix our signatures.

EMERY L. WALKER.
ARTHUR W. WERNER.
